U.S. Appl. No. 29/497,626; Filing Date: Jul. 25, 2014; "Vehicle Rail Extension".

Primary Examiner — Darlington Ly

(74) Attorney, Agent, or Firm — Cantor Colburn LLP

(57) **CLAIM**

The ornamental design for a vehicle rail extension, as shown and described.

DESCRIPTION

FIG. 1 is a front perspective view of a vehicle rail extension showing our new design;

FIG. 2 is a rear perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines shown in the figures illustrate portions of the vehicle rail extension that form no part of claimed design.

1 Claim, 4 Drawing Sheets(56)
